UNITED STATES PATENT OFFICE.

MARK LAMBERT BRISTOL AND HOLDEN CHESTER RICHARDSON, OF THE UNITED STATES NAVY.

FLOAT FOR AEROPLANES.

1,213,453.

Specification of Letters Patent. Patented Jan. 23, 1917.

Application filed February 21, 1916. Serial No. 79,695.

To all whom it may concern:

Be it known that we, MARK LAMBERT BRISTOL and HOLDEN CHESTER RICHARDSON, both of the United States Navy, and citizens of the United States, stationed at Washington, in the District of Columbia, have invented certain new and useful Improvements in Floats for Aeroplanes; and we do hereby declare the following to be a full, clear, and exact description of the invention, such as will enable others skilled in the art to which it appertains to make and use the same.

Our invention relates to improvements in aeroplanes, and it is intended to provide an aeroplane that will have the following qualities: stability at rest in smooth or rough water; ready steering on the surface in smooth or rough water; absence of danger when skidding in smooth or rough water; diminution of squatting; reduction of shocks on landing, or when running on rough water at high speeds; early planing; practical absence of porpoising; practical absence of disturbing forces when making or breaking contact with the surface; easy penetration of curling wave crests; protection of the propeller and of the wing tips in rough water; adequate stability when even solid water passes over the floats; and minimum resistance of the floats in flight through the air. All of these advantages are in a large measure obtained by use of the apparatus hereinafter described.

Reference is had to the accompanying drawings, in which similar parts are indicated by similar reference symbols throughout the several views.

Figure 1 is a perspective view showing the central portion of a hydroaeroplane with the improved floats attached; Fig. 2 is a plan view of the floats shown in Fig. 1, parts being broken away, and most of the bracing being omitted for the sake of clearness in the drawings; Fig. 3 is a side elevation showing the central float, and one of the side floats, on a larger scale than in Fig. 1; Fig. 4 shows a central longitudinal vertical section, or "inboard profile," through the central or main float, the keel being shown in elevation; Fig. 5 shows a central longitudinal vertical section, or "inboard profile," through one of the smaller floats; Fig. 6 shows a section along the line 6-6^a of Fig. 2, and looking in the direction of the arrows; Fig. 7 shows a section along the line 7-7^a

of Fig. 2, and looking in the direction of the arrows; Figs. 8, 9, 10 and 11 show sections corresponding to the lines 8-8^a, 9-9^a, 10-10^a and 11-11^a of Fig. 4, and looking in the direction of the arrows; Figs. 12 and 13 show sections along the lines 12-12^a and 13-13^a of Fig. 5, and looking in the direction of the arrows; Fig. 14 shows what is known in shipbuilding as a "body plan" of the main float, the lines on the right-hand side of the figure indicating the sections as seen from the bow of the float, and the lines on the left-hand side of the figure indicating the sections as seen from the stern of the float; and Fig. 15 shows a body plan of one of the side floats, the figure illustrating the right-hand side float looking aft.

A represents a biplane of any suitable type, provided with the usual planes or wings A' and A''.

We do not mean to limit our invention to any particular type of aeroplane, and it is intended to be applied to a biplane, or monoplane, or other heavier than air flying machines of suitable type.

The present invention relates especially to the construction and arrangement of the group of floats which are carried by the aeroplane and support the same when in the water, and which are constructed of stream-line form to minimize the resistance of the air, and also to penetrate the crest of waves. There are three of these floats connected together in a group, as shown in Figs. 1 to 7, and comprising a central or main float B, and two side floats D and D' connected to the main float, and to each other, by suitable trusses C, C', C'' and C^a, shown most clearly in Fig. 1. The two smaller floats D are preferably located nearer the longitudinal axis of the main float, which corresponds to the central longitudinal axis of the complete machine, than are the tips of the wings, so that when the machine is lighting, the smaller side floats will engage the water before the tips of the wings can do so, and thus there will be no excessive strain brought on the tips of the wings. In practice, we locate these side floats at about one-third or two-fifths the distance from the center of the machine to the tip of the wing. The arrangement of these trusses would vary with the construction of the aeroplane, and may be varied at will. Any suitable construction of sufficient strength and elasticity to

attach the floats to the aeroplane may be adopted.

We do not claim any special method of bracing the floats, or connecting the same to the aeroplane.

5 The main float B should be of sufficient buoyancy to support the weight of the aeroplane and its load, and the smaller floats with the main float should have sufficient 10 reserve buoyancy for the successful operation of the aeroplane. The smaller side floats are arranged at each side of and abreast the rear portion of the main float, as shown in Fig. 2, and these floats are so 15 arranged that the center of gravity of the aeroplane will practically coincide with the center of flotation of the group of floats indicated by X in Figs. 2 and 3. The advantage of this arrangement will be hereinafter 20 more fully described. The main float B is made of stream-line form, as shown, and is provided with a curved upper portion b, as shown in Figs. 6 to 11 and 14, and has its bottom slightly warped fore and aft, but 25 rectilinear in cross section, as shown in Figs. 6 to 11 and 14, the two sides of the bottom converging toward the central keel. The two flaring sides of the bottom are slightly warped in reverse directions fore and aft, as shown in Fig. 14, for reasons that will 30 hereinafter be described. The main float B is made preferably of the stepped construction, the step being shown at B', and suitable air inlets b' are provided to admit air 35 to break the suction created by the step, and thus to diminish suction effects when the aeroplane is forging ahead rapidly upon the surface of the water. The main float B is also provided with a suitable keel B² mainly 40 for landing purposes. The shell of the float, if of wood, is preferably made of multiple thicknesses of planking, such as two-ply spruce planking with cloth and water-proof glue between the layers, so as to make the 45 same water-tight. On the interior we provide a center keelson B³ running the full length of the float, and we also provide suitable transverse ribs b², transverse water-tight bulk heads b³, stanchions b⁴ and fore 50 and aft bracing b⁵. The central portion of the float on which the main shock is felt in landing, or in striking the water with great force, is provided with a vertical longitudinal bulk head b⁶, and intermediate keelsons 55 b⁷, or longitudinal frames, are also provided. The transverse bulk heads b⁸, if of wood, are preferably made of multiple thicknesses of planking, one placed horizontally and others placed diagonally, as shown in 60 Figs. 9 and 10, so that great strength is secured against blows on the bottom of the float as when striking the water at high speed. The boards of the longitudinal bulk head b⁶ and the braces b⁵ are for similar reasons made inclined, as shown, so as to stiffen 65

the hull of the float when striking the water. Other suitable stiffening means may be provided on the interior of the floats, such as the frames b⁸, shown in Figs. 9, 10 and 11, and the struts b⁹, shown in Figs. 6 and 7.

70 By the construction shown the main float is divided into a series of water-tight compartments, two being shown in the forward portion of the float, one in the stern portion, and two in the central portion, separated by the central fore and aft bulk head b⁶.

75 The construction of the smaller floats D and D' is generally similar to that of the large float already described, these floats having a rounded upper surface d, as shown in Figs. 12 and 13, and warped bottoms d' which are rectilinear in cross section. On the interior these floats are provided with keelsons d⁰ and d² running fore and aft, and with transverse bulk heads d³, and with 80 suitable braces d⁴, preferably diagonally disposed to give longitudinal stiffness to the float, and with struts d⁵. The transverse bulk heads d⁶, if of wood, are preferably 85 made of multiple layers, as shown in Fig. 13, and separate the body of the floats into a series of water-tight compartments, as well as adding stiffness to the float. Preferably both the large and the smaller floats have 90 stream-line form, as shown in the drawings, 95 more especially in Figs. 14 and 15, in which the nature of the warped bottom of the main and smaller floats is indicated by the inclined straight lines, and the curved top portion of said floats indicated by the 100 curved lines. The curved dotted lines indicate the position of the side keelsons. The line L—W—L indicates the load water line. The several sections shown in Fig. 14 indicated by the lines 2, 4, 6, 8, 10, 12, 14 and 105 16 correspond with the sections along the line 2—2, 4—4, etc., and 18—18 of Fig. 2; and the lines 2', 4', 6', 8' of Fig. 15 corresponding to sections along the line 2'—2', 4'—4', 6'—6' and 8'—8' of Fig. 2, respectively. 110 It will be noted that these bottom section lines 2 to 18 and 2' to 8' are not parallel, but in the larger float the bottom surface is warped to form a warped surface of double curvature; while in the smaller 115 floats the bottom surface is warped to form a warped surface of single curvature.

116 The advantage of the warping of the main float is to provide the necessary cushioning near the step, and at the same time to provide ample bearing power at the bow, to prevent the nose from being buried on a landing. The change in flare of the side floats is to provide a similar cushioning effect, and also the increased angle of flare 120 at the bow is to prevent the side floats from burying the nose on a skidding landing.

125 The floats are preferably so adjusted relative to the aeroplane that when at rest on smooth water the floats are down by the 130

stern somewhat, as indicated by the line W—L in Figs. 3, 4 and 5. This causes the vertical axis of the aeroplane to tilt backward at a small angle indicated by θ in Fig. 3, which angle is preferably about 3° . This gives a very advantageous angle for the planing effect in starting, and also gives the wings a greater lifting angle, both tending to cause planing more readily.

It will be seen that we provide a central float of suitable stream-line form and construction of the hydroplane type, of such proportions as to support the major portion of the displacement at rest, together with suitable reserve buoyancy, and so formed as to resist and reduce shocks on landings, or when planing at high speed in rough water; also so shaped as to avoid danger due to skidding on the surface. In addition to this central float we provide symmetrically rearwardly, laterally and relatively upwardly-disposed floats of suitable stream-line form and hydroplane type, and of such proportion as to provide a minor portion of the displacement at rest, together with suitable reserve buoyancy; and so formed as to resist and reduce shocks on landing or when planing at high speed in rough water; and also so formed as to avoid danger due to skidding on the surface and, at the same time, of such form as to assist in steering; the whole being designed so that at rest the floats are trimmed by the stern about 3° , the center of buoyancy then being immediately under the center of gravity.

The operation of the apparatus is as follows:—Suppose the aeroplane to be at rest on the water, and it be desired to get away, as the boat skims along the water the wings and the bottoms of the floats cause it to lift on an even keel, and the side floats will be the first to be lifted out of the water, leaving the lower portion of the main float submerged, and as the speed increases above a certain point the flow from the step of the main float clears the after portion of the main float, the remaining load now being carried at the step, and the main float will shortly thereafter be lifted clear of the water, and the aeroplane will continue its flight through the air. Now in the process of rising from the water, the planing of the two side floats, before the speed gets very high, will prevent any material squatting, and they assist in breaking the suction to the rear of the step of the main float, and thus the equivalent of the well known stepped type is secured, without the defects inherent in that type where the steps work in the wake of the forward portion.

Should the sea be choppy, or rough, the shape of the floats will permit them to readily penetrate the crests of the waves.

Among other features and advantages of

the hereinbefore described construction and operation we may include the following:—

At rest or adrift.—The load is distributed to the three points of support in such a manner that each support carries its designed proportion of the load and provides the required stability on the surface with reserve buoyancy and range of stability to the required degree.

The centralized group avoids undue stress on the wing structure and provides initial stability in contradistinction of the instability of the usual three-float arrangement with the planing floats on the wing tips. No tail floats are required to prevent tipping over backward. This arrangement of floats has structural advantages, concentrating the principal weight and strength members so that the principal members contribute strength where required, and thus avoiding undue stresses on the wing structure when getting away, flying, or landing, such as are involved when wing tip floats, or twin floats, are used. The reserve buoyancy is preferably such that the central float has a total displacement at least equal to the full load of the aeroplane, so that when riding the crest of a wave the propeller and wing clearances are still the same as the clearance from the deck of the main float, and in a trough, unless it is a sharp one, the side floats are satisfactorily elevated relative to the central float, so that the principal load is still carried on the central float. To appreciate the advantage this affords, it should be noted that twin floats straddle crests and thus in choppy water endanger a central propeller, which would be protected in a triple float type. Also, in a triple float the stability is due more to separation of floats than to the displacement of the lateral floats; and though equal stability is provided the rolling couples, on account of the elevation of the side floats, provide more flexibility, and the action is less harsh than with a twin float disposition in which half the load is carried necessarily on each float.

Under way.—As the side floats carry load up to a certain speed their planing bottoms provide the additional surface required for planing up to the time that the main float has sufficient planing power to handle the remaining load. The transition is progressive, and the planing bottoms of the side floats are in effect a variable "step" which is designed to work clear of the wake of the forward bottom (of the main float). This type is more efficient, planes quicker, and reduces the porpoising tendency present in the usual step type; in fact, the side floats act under way as dynamic stabilizers, laterally and longitudinally, acting in conjunction with the air controls up to the time the latter are sufficient for the purpose. Due to the flaring form of the bottoms of the

115
120
125
130

1
side floats, they also offer strong dynamic forces resisting overturning sidewise when skidding on the surface, and this same form of bottom materially assists in steering on 5 the surface because the higher speed of the outer float on a turn causes it to plane better than its partner, which action combined with the skidding action above referred to causes the inboard float to drag 10 harder, and thus provides a strong turning moment in addition to that provided by the air rudder.

At a moderate speed, due to the assistance 15 of the planing powers of the bottoms of the side floats, the planing power of the main float is improved, as it cannot squat; and the planing of the system is inaugurated at an early stage, and the transition 20 from planing on all three floats to planing on the central float is smooth and rapid.

The bottom of the main float has a V 25 form for the purpose of breaking the shock on landing, or when running over the surface of rough water at high speed. This natural shock absorber avoids the necessity 30 of mechanical shock absorbers in the supporting members. This form also avoids danger when skidding on the surface. The central system is so arranged that the first 35 point of contact on landing is on the bottom of the main float nearly under the center of gravity. This affords structural advantages due to the centralization of the disturbing forces involved when contact with the 40 surface is made, or broken, and the V-bottom also contributes to reduce the sharpness with which these forces come into play.

It will be obvious that various modifications 45 might be made in the herein described apparatus, and in the construction, combination and arrangement of parts which could be used without departing from the spirit of our invention.

Having thus described our invention what 45 we claim and desire to secure by Letters Patent of the United States is:—

1. A float attachment for aeroplanes, comprising a main central float mounted below the center of gravity of the aeroplane and 50 provided with a substantially V-shaped bottom, and two smaller side floats secured abreast the rear portion of the main float, the three floats being mounted below and connected to the body of the aeroplane, and 55 said side floats having their bottoms flared outward in reverse directions, substantially as described.

2. A float attachment for aeroplanes, comprising a main central float mounted below 60 the center of gravity of the aeroplane, said float being of stream-line construction having its upper surface curved and tapering forward and aft, and its bottom substantially V-shaped in cross section, and two 65 smaller side floats secured abreast the rear

portion of the main float, the two side floats having their upper surface curved and tapering fore and aft and their bottoms flaring upward and outward in reverse directions, the three floats being also connected to the body of the aeroplane, substantially as described. 70

3. A float attachment for aeroplanes, comprising a main central float mounted below the center of gravity of the aeroplane, said 75 float being of stream-line construction having its upper surface curved and tapering forward and aft, and its bottom substantially V-shaped in cross section, and provided with a step, and two smaller side floats secured abreast the rear portion of the main float, the two side floats having their upper surface curved and tapering fore and aft and their bottoms flaring upward and 80 outward in reverse directions, the three floats being also connected to the body of the aeroplane, substantially as described. 85

4. A float attachment for aeroplanes, comprising a main central float mounted below the center of gravity of the aeroplane, said 90 float being of stream-line construction having its upper surface curved and tapering forward and aft, and its bottom substantially V-shaped in cross section, and provided with a step, with means for ventilating said step, and two smaller side floats secured abreast the rear portion of the main float, the two side floats having their upper surface curved and tapering fore and aft and their bottoms flaring upward and outward in reverse directions, the three floats 95 being also connected to the body of the aeroplane, substantially as described. 100

5. A float attachment for aeroplanes, comprising a main central float mounted below 105 the center of gravity of the aeroplane, said float being of stream-line construction having its upper surface curved and tapering forward and aft, and its bottom substantially V-shaped in cross section, and two 110 smaller side floats secured abreast the rear portion of the main float, the two side floats having their upper surface curved and tapering fore and aft and their bottoms of warped construction and flaring upward and 115 outward in reverse directions, the three floats being also connected to the body of the aeroplane, substantially as described.

6. A float attachment for aeroplanes, comprising a main central float mounted below 120 the center of gravity of the aeroplane, said float being of stream-line construction having its upper surfaces curved and tapering forward and aft, and its bottom substantially V-shaped in cross section, and provided with a step, and two smaller side floats secured abreast the rear portion of the main float, the two side floats having their upper surface curved and tapering fore and aft and their bottoms of warped construction 125 130

tion and flaring upward and outward in reverse directions, the three floats being also connected to the body of the aeroplane, substantially as described.

5 7. A float attachment for aeroplanes, comprising a main central float mounted below the center of gravity of the aeroplane, said float being of stream-line construction having its upper surface curved and tapering forward and aft, and its bottom substantially V-shaped in cross section, and provided with a step, with means for ventilating said step, and two smaller side floats secured abreast the rear portion of the main 10 float, the two side floats having their upper surface curved and tapering fore and aft and their bottoms of warped construction and flaring upward and outward in reverse directions, the three floats being also connected to the body of the aeroplane, substantially as described.

15 8. A float attachment for aeroplanes, comprising a main central float mounted below the center of gravity of the aeroplane, and two smaller side floats secured abreast the rear portion of the main float, the two side floats having their upper surface curved and tapering fore and aft and their bottoms of warped construction and flaring upward and outward in reverse directions, the three floats being also connected to the body of the aeroplane, substantially as described.

20 9. A float attachment for aeroplanes, comprising a main central float mounted below the center of gravity of the aeroplane, said float being of stream-line construction having its bottom substantially V-shaped in cross section, and provided with a step, and two smaller side floats secured abreast the rear portion of the main float, the two side floats having their upper surface curved and tapering fore and aft and their bottoms of warped construction and flaring upward and outward in reverse directions, the three floats being also connected to the body of the aeroplane, substantially as described.

25 10. A float attachment for aeroplanes, comprising a main central float mounted below the center of gravity of the aeroplane, said float being of stream-line construction, its bottom substantially V-shaped in cross section, and provided with a step, with means for ventilating said step, and two smaller side floats secured abreast the rear 30 portion of the main float, the two side floats having their upper surface curved and tapering fore and aft and their bottoms of warped construction and flaring upward and outward in reverse directions, the three floats being also connected to the body of the aeroplane, substantially as described.

35 11. A float attachment for aeroplanes, comprising a main central float mounted below the center of gravity of the aeroplane, said float being of stream-line construction,

40 and its bottom substantially V-shaped in cross section, and two smaller side floats secured substantially abreast the rear portion of the main float, the two side floats having their upper surface curved and tapering 70 fore and aft and their bottoms flaring upward and outward in reverse directions, the three floats being also connected to the body of the aeroplane, and forming a central triangular support therefor when engaging the water, substantially as described.

45 12. A float attachment for aeroplanes, comprising a main central float mounted below the center of gravity of the aeroplane, said float being of stream-line construction 80 having its upper surface curved and tapering forward and aft, and its bottom substantially V-shaped in cross section, and provided with a step, and a keel, and two smaller side floats secured substantially 85 abreast the rear portion of the main float, the two side floats having their upper surface curved and tapering fore and aft and their bottoms flaring upward and outward in reverse directions, the three floats being 90 also connected to the body of the aeroplane, and forming a central triangular support therefor when engaging the water, substantially as described.

95 13. A float attachment for aeroplanes, comprising a main central float mounted below the center of gravity of the aeroplane, said float being of stream-line construction having its upper surface curved and tapering forward and aft, and its bottom substantially 100 V-shaped in cross section, and provided with a keel and a step, with means for ventilating said step, and two smaller side floats secured substantially abreast the rear portion of the main float, the two side floats 105 having their upper surface curved and tapering fore and aft and their bottoms flaring upward and outward in reverse directions, the three floats being also connected to the body of the aeroplane, and forming a central 110 triangular support therefor when engaging the water, substantially as described.

115 14. A float attachment for hydroaeroplanes, comprising a main central float mounted below the center of gravity of the aeroplane, and two smaller side floats secured abreast the rear portion of the main float, extending from points substantially opposite the center of the main float and extending to points substantially opposite the stern of the main float, said smaller floats being located nearer the center of the wings than the tips thereof, the three floats being mounted below and connected to the body of the aeroplane, substantially as described.

120 15. A float attachment for hydroaeroplanes, comprising a main central float mounted below the center of gravity of the aeroplane, and provided with a substantially V-shaped bottom, and two smaller side floats 125

secured abreast the rear portion of the main float, and having their rear ends terminating at points substantially in line with the rear end of the main float, said smaller floats being located nearer the center of the wings than the tips thereof, the three floats being mounted below and connected to the body of the aeroplane, substantially as described.

16. A float attachment for aeroplanes, comprising a main central float mounted below the center of gravity of the aeroplane, said float being of stream-line construction having its upper surface curved and tapering forward and aft, and its bottom substan-

tially V-shaped in cross-section, and two 15 smaller side floats spaced away from and secured abreast the rear portion of the main float, and having their rear ends terminating at points substantially in line with the rear end of the main float, said smaller floats being located nearer the center of the wings than the tips thereof, the three floats being also connected to the body of the aeroplane, substantially as described.

20 In testimony whereof, we affix our signatures.

MARK LAMBERT BRISTOL.
HOLDEN CHESTER RICHARDSON.
